PHOTOELECTRIC TUBE

Oran T. McIlvaine, St. Charles, Ill.

Original application September 9, 1944, Serial No. 553,411. Divided and this application July 29, 1948, Serial No. 41,383

10 Claims. (Cl. 250—168)

1

This application is a division of my prior application filed September 9, 1944, Serial No. 553,411 now Patent 2,451,400.

This invention relates to improvements in photo-electric tubes.

It has been customary heretofore to construct photo-electric tubes with anodes and cathodes, which are sometimes arranged in multiple in a single envelope, but this has involved multiplying both the anodes and cathodes, whereby a single anode would be arranged in association with a single cathode surface. Where the cathode surface is extended appreciably, this causes the electrons emitted from the cathode to travel in converging or diverging directions toward the anode, whereby such arrangements cannot be utilized to advantage in transmitting intelligence, photographic or code arrangement of dots, or for causing illumination of a bank of lights in a particular code or series, such as is often desired. These arrangements have heretofore required separate photo-electric cells for each point of light or other element to be reproduced or transmitted, which has made it impractical to transmit fine detail in pictures or to depict these on a bank of lights.

The object of this invention is to improve the construction of a photo-electric tube for this purpose, to enable it to be used for the different applications mentioned, one tube replacing the multiplicity of tubes required heretofore which, nevertheless, makes possible the transmission of pictures of fine detail in a more practical manner than has been possible with the multiplicity of photo-electric tubes as required heretofore.

This object is accomplished by utilizing a plurality of anodes associated with a single cathode, so arranged that the electrons emitted from the cathode surface will travel substantially in parallel directions to the adjacent anodes, whereby the electrons from a particular portion or spot on the cathode will go to a certain anode directly opposite this spot or portion. By this means any picture or pattern of shadow put on the cathode will cause the corresponding group of anodes to receive selectively the emission, and by arranging the number of anodes in sufficiently close relation and smallness of shape, the desired definition can be obtained, comparable with the usual photograph for instance.

Each anode may be used to control a separate electrical device, such as a lamp, relay or the like in direct response to the passage of light onto the corresponding spot or portion of the cathode. The anodes can be arranged in close relation without interference by reason of

2

their association with a cathode whereby the electrons travel in parallel relation from the cathode surface to the corresponding anodes.

I have shown one embodiment of this invention in the accompanying drawings in which:

Fig. 1 is a side elevation of a photo-electric tube embodying this invention;

Fig. 2 is an end elevation thereof; and

Fig. 3 is a detail sectional view through one of the anode mountings.

One form of photo-electric tube is shown in Figs. 1 to 3, in which the tube is designated generally by the numeral 21 and has a cathode 23 mounted therein arranged to receive light through a side of the tube or through a window formed at a side thereof in the customary manner. The anodes are designated generally at 24, a multiplicity of which are mounted in an end of the tube 21, as will be evident from Fig. 1.

I have shown the anodes 24 as formed by wires slightly spaced from each other, and fused together in glass beads 26, which form the end of the tube 21. The wires are arranged substantially in a bundle, and when fused in this way they provide a multiplicity of anodes fixed in the end of the tube and insulated from each other, as will be evident from Figs. 1 to 3. The size of these and the relative spacing thereof is appreciably exaggerated for clearness of illustration, it being evident that only fine wires are required and closely spaced from each other, so that an appreciable bundle of 100 wires per square inch may be used in a single tube.

The end of each wire forms a tiny anode surface facing the cathode 23, so as to receive electron therefrom corresponding in position with the points on the cathode to which light is directed from the film or other light means. Such an arrangement of a cathode with a multiplicity of anodes causes the electron paths to travel in parallel directions and in straight lines from the cathode to the anode, so as to be directed onto particular anodes according to the spots on the cathode receiving light from the picture or pattern.

Thus not only will portions of the reproduced picture or other pattern be illuminated or depicted, but shadows and variations in shade will be reproduced also corresponding with those on the pattern. Therefore, it is necessary merely to have as large a number of anodes as is required to get the desired detail, which can be arranged conveniently and satisfactorily without the necessity for assembling a large number of separate and independent photo-electric tubes as has been required heretofore.

The form of tube here shown may be used

wherever desired in the usual manner of using a photo-electric or light sensitive tube. Various uses will occur to those skilled in the art which need not be set forth in detail, although I may describe one application thereof as an example.

The anodes may be connected in the grid circuits of corresponding amplifier tubes, the output sides of which are connected with corresponding respective incandescent lamps, one being arranged for each anode. These electric lamps may be connected in a bank so as to produce lights in the bank or sign in which they are used corresponding with the spots on the cathode that may receive light, one lamp being energized for each spot of light directed on the cathode.

Thus by arranging the lamps in a large bank covering a substantial area, with a corresponding anode for each lamp, it is possible to reproduce on the lights many different pictures or other effects, or to use this principle in business machines for sorting or tabulating from characters on film or paper. By exposing a film or paper to the cathode, lamps corresponding with the spots thereof will be ignited and the picture, film or the like will be reproduced in the bank of lamps. The arrangement of the multiplicity of anodes in association with a cathode causes the electron streams to travel in parallel directions from the cathode surface to the corresponding anodes, thus making it possible to reproduce accurately the film, picture or the like, according to the spots of light applied to the cathode.

This arrangement makes it possible for the electrons from any particular spot on the cathode to be directed to a corresponding certain anode. Since each anode is connected in a separate and independent circuit, it may have a different current from the others, whereby it can cause a reproduction of light to varying degrees, so as to produce light and dark shadows in the reproduced picture.

This principle is operable in many different systems, as for instance, it can be used for operating relays instead of for energizing incandescent lamps merely by making the proper substitution in the energizing system. It may be used as a basis for an automatic tabulating machine operated in response to code or other cards or film, replacing the large number of individual photo-electric cells heretofore required.

The tube may be evacuated and the electrodes treated in the usual way of preparing a photo-electric tube, particularly in preparing the cathode to be light responsive.

While the invention has been illustrated and described in one embodiment, it is recognized that variations and changes may be made therein, without departing from the invention, except as specified in the claims.

I claim:

1. In a photo-electric tube, the combination with a cathode surface, of a plurality of anode surfaces arranged to receive electron streams along substantially parallel lines from respectively different portions of the cathode surface.

2. In a photo-electric tube, the combination

with a cathode surface, of a plurality of anode surfaces arranged in cooperating relation with the cathode surface in position to receive electronic emission from the cathode surface along substantially parallel lines to the respective anode surfaces.

3. In a photo-electric tube, the combination with a cathode surface, of a multiplicity of anode surfaces arranged substantially parallel with the cathode surface and in position to receive electronic emission therefrom along substantially parallel lines from the cathode surface to the respective anode surfaces.

4. In a photo-electric tube, a multiplicity of anodes comprising conductive elements having spot anode surfaces thereon.

5. In a photo-electric tube, the combination with a cathode surface, of a plurality of anode surfaces comprising conductive elements each having an anode surface thereon.

6. A photo-electric tube comprising an envelope having a cathode surface mounted therein, and a plurality of anodes arranged in cooperating relation with said cathode, each of the anodes comprising a wire having an anode surface directly thereon.

7. A photo-electric tube comprising an envelope having a cathode surface mounted therein, and a plurality of anodes arranged in cooperating relation with said cathode, each of the anodes comprising a wire having an anode surface directly on the end thereof.

8. A photo-electric tube comprising an envelope having a cathode surface mounted therein, and a plurality of anodes arranged in cooperating relation with said cathode, each of the anodes comprising a wire having an anode surface on the end thereof, said anode wires being arranged in a bundle and respectively embedded in insulating material separating the wires from each other and mounting the same in the envelope.

9. A photo-electric tube comprising an envelope having a cathode surface therein, a plurality of glass beads arranged in a bundle in the envelope and fused together, a wire extending through each of the beads and supported thereby, and means forming an anode surface on each of the wires in cooperating relation with the cathode surface.

10. A photo-electric tube comprising an envelope having a cathode surface therein, and a plurality of wires extending in spaced parallel relation in the envelope, each of the wires having an anode surface directly on the end thereof circumscribed by the periphery of the wire.
